SCAFFOLD SUPPORT

Clarence F. McQuin, Milwaukee, Wis.

Application April 8, 1949, Serial No. 86,357

1 Claim. (Cl. 304—4)

1

This invention relates to scaffold supports or scaffold jacks and more particularly to an improved tripod jack or support for holding platform boards in an elevated position.

It is among the objects of the invention to provide an improved tripod jack that can be quickly and easily collapsed or folded for storage and transportation and unfolded or spread to operative condition, that is fully adjustable as to height and leveling, that is easily and securely locked in adjusted condition, that is strong and sturdy in construction, will support boards or planks in either a flat or on edge position, is light in weight and economical to manufacture.

Other objects and advantages will become apparent from a consideration of the following description and appended claim in conjunction with the accompanying drawing wherein:

Figure 1 is an elevation of a tripod scaffold jack illustrative of this invention; and

Figure 2 is an elevation of the fragmentary upper portion of the jack with such upper portion turned ninety degrees from the position illustrated in Figure 1.

With continued reference to the drawing, the improved tripod jack has an elongated tubular stem 10. A tubular sleeve 11 is slidable on the stem and carries a set screw 12, or equivalent fastener, for securing the sleeve in adjusted position longitudinally of the stem. Apertured lugs 13 extend outwardly of the sleeve 11 near the upper end thereof and are disposed at their substantially equally spaced locations around the sleeve. Three tubular upper leg sections 14 have their upper ends flattened and apertured and pivotally secured to corresponding lugs 13 by respective pivot pins 15.

A bracket 16 is secured on stem 10 adjacent the lower end of the latter and apertured lugs 17 extend outwardly from the bracket at substantially equally spaced locations therearound.

A respective apertured lug 18 extends outwardly from each upper leg section 14 near the lower end of the latter and links 19 are pivotally connected one to each lug 18 at one end of the link and at its opposite end to a corresponding lug 17 on the bracket.

Cylindrical lower leg sections 20 are telescopically secured one in each tubular upper leg section 14 and suitable pads 21 of resilient material are provided one on the lower end of each lower leg section. Set screws 22 are carried one by each upper leg section 14 and these set screws are engageable with the corresponding

2

lower leg sections to secure the lower sections in adjusted position in the upper sections.

A cylindrical socket 23 is releasably secured on the upper end of stem 10 by a set screw 24 or other suitable fastener and a plank supporting plate 25 is secured to the socket.

Plate 25 is an elongated, rectangular body of thin, strong metal, such as steel, and has upwardly extending flanges 26, one at each end substantially perpendicular to the adjacent portions of the plate, and a U-shaped formation 27 at substantially the mid length location of said plate.

Plate 25 will receive a plank 28 in flat position between the flanges 26 and will receive a plank on edge in the U-shaped formation 27 so that flat positioned planks may be supported on edges of planks to provide a platform of desired size.

20 Two or more of the improved jacks may be used depending upon the size of the structure to be worked on. For example, four such jacks disposed one in each corner of a dwelling house room and supporting two planks on edge and the necessary number of flat planks will permit the entire ceiling of such a room to be worked on from a single scaffold platform.

The jacks may be made in various sizes as to height and in different weights depending upon the loads to be carried thereby.

30 The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the 40 claim is, therefore, intended to be embraced therein.

What is claimed is:

A headplate for a scaffold jack tripod comprising a cylindrical stem receiving socket and 45 an elongated metal strip mounted on said socket, said strip having its opposite end flanges extending perpendicularly in the same direction therefrom and having at its mid-length location a U shaped formation extending from said strip in 50 the direction opposite said flanges and secured at its end remote from the remainder of said strip to said socket, said headplate having between said flanges a length sufficient to receive the width of a scaffold board and said U shaped 55 formation having an interior width sufficient to

receive the thickness of a scaffold board and a depth sufficient to firmly support such a board in an edgewise position.
